UNITED STATES PATENT OFFICE

167,570

PUZZLE CHARM OR SIMILAR ARTICLE

Raymond Haines, Philadelphia, Pa., assignor to
Champion Plastics Corp., New York, N. Y., a
corporation of New York

Application May 28, 1952, Serial No. 19,930

Term of patent 3½ years

(Cl. D45—17)

To all whom it may concern:

Be it known that I, Raymond Haines, a citizen of the United States, residing at Philadelphia, in the county of Philadelphia and State of Pennsylvania, have invented a new, original, and ornamental Design for a Puzzle Chain or Similar Article, of which the following is a specification, reference being had to the accompanying drawing, forming part thereof.

In the drawing:

Fig. 1 is a bottom view of a puzzle charm or similar article, showing my new design;

Fig. 2 is a side elevational view thereof; and
Fig. 3 is a top plan view thereof.

I claim:

The ornamental design for a puzzle charm or similar article, substantially as shown.

RAYMOND HAINES.
